(57) **CLAIM**

The ornamental design for a mobile air conditioner, as shown and described.

DESCRIPTION

The file of this patent contains at least one drawing/photograph executed in color. Copies of this patent with color drawing(s)/photograph(s) will be provided by the Office upon request and payment of the necessary fee.

1. Mobile air conditioner

1.1 : Front

1.2 : Back

1.3 : Left

1.4 : Right

1.5 : Top

1.6 : Perspective

The product is used to adjust the indoor temperature and humidity; the gist of the present design is the shape best shown in the perspective view; the bottom view has been omitted because it does not contain claimable elements.

**1 Claim, 6 Drawing Sheets
